UNITED STATES PATENT OFFICE

SIDNEY A. KELLER, OF NEW YORK, N. Y.

DESIGN FOR A HANDLE FOR BUTTON-HOOKS OR SIMILAR ARTICLES.

SPECIFICATION forming part of Design No. 36,024, dated August 26, 1902.

Application filed July 23, 1902. Serial No. 116,745. Term of patent 3½ years.

To all whom it may concern:

Be it known that I, SIDNEY A. KELLER, a citizen of the United States, and a resident of New York, borough of Manhattan, in the county of New York and State of New York, have invented and produced a certain new, original, and ornamental Design for a Handle for Button-Hooks or Similar Articles, of which the following is a specification.

5 In the accompanying drawing I have shown a face view of a handle for button-hooks or similar articles ornamented in accordance with my invention, the hook being shown in dotted lines.

5 The leading or characteristic features of my design are the outline or contour, consisting of compound curves, the head of a female figure having wings extending therefrom and occupying the upper portion of the handle, and floral decoration below the head and forming the border of a plain shield occupying the lower portion of the handle.

Referring to the drawing, A represents the head of a female figure, from which extend upwardly the wings B B, the lower portion of 25 the handle being occupied by the floral decoration C C and a plain shield D, the ornamentation being in relief.

What I claim is—

The ornamental design for a handle for button-hooks or similar articles, substantially as herein shown and described.

Signed at New York, borough of Manhattan, in the county of New York and State of New York, this 21st day of July, A. D. 1902. 35

SIDNEY A. KELLER.
